SAFETY BELT BUCKLE

George H. Jantzen, New York, N.Y., assignor to M.
Steinthal & Company, Incorporated, New York, N.Y.,
a corporation of New York

Filed Mar. 7, 1967, Ser. No. 6,101

Term of patent 14 years

(Cl. D2—408)

FIG.1

FIG.2

FIG.3

FIG.4

FIG. 6

FIG. 7

FIG. 8

FIG. 5

FIG. 9

FIGURE 1 is a top plan view of a safety belt buckle showing my new design;

FIGURE 2 is a side elevation view of the form shown in FIGURE 1;

FIGURE 3 is an end elevation view of the form shown in FIGURE 1;

FIGURE 4 is an end elevation view of the form shown in FIGURE 1 and opposite to the end shown in FIGURE 3;

FIGURE 5 is a bottom plan view of the forms shown in FIGURE 1 and FIGURE 6;

FIGURE 6 is a top plan view of a safety belt buckle showing another form of my design with a raised cover;

FIGURE 7 is a side elevation view of the form shown in FIGURE 6;

FIGURE 8 is an end elevation view of the form shown in FIGURE 6;

FIGURE 9 is an end elevation view of the form shown in FIGURE 6 and opposite to the end shown in FIGURE 8.

The part with which the safety belt buckle mates is shown in dotted lines for illustrative purposes only.

I claim:

The ornamental design for a safety belt buckle, substantially as shown and described.
